(57) **CLAIM**

The ornamental design for a speaker stand, as shown and described.

DESCRIPTION

FIG. 1 is a front perspective view of a speaker stand, showing an example environment

FIG. 2 is a front view of the speaker stand of FIG. 1;

FIG. 3 is a rear view of the speaker stand of FIG. 1;

FIG. 4 is a left-side view of the speaker stand of FIG. 1;

FIG. 5 is a right-side view of the speaker stand of FIG. 1;

FIG. 6 is a top plan view of the speaker stand of FIG. 1;

FIG. 7 is a bottom plan view of the speaker stand of FIG. 1;

FIG. 8 is a front perspective view of the speaker stand; and,

FIG. 9 is a top plan view of the speaker stand of FIG. 8.

The dash-dot-dot-dash broken line immediately adjacent the solid-line portions of the design represents an unclaimed boundary of the design. Features shown in other broken lines in FIGS. 1, 2, 3, 4, 5, 6, and 7, form no part of the claimed design.
